UNITED STATES PATENT OFFICE.

HEINRICH O. BRANDT, OF MANCHESTER, ENGLAND.

METHOD AND APPARATUS FOR ATOMIZING AND SPRAYING OILY MATERIALS.

No. 913,686.

Specification of Letters Patent.

Patented March 2, 1909.

Application filed December 6, 1905. Serial No. 290,644.

To all whom it may concern:

Be it known that I, HEINRICH OTTO BRANDT, German subject, and resident of Manchester, county of Lancaster, England, have invented 5 certain new and useful Methods and Apparatus for Atomizing and Spraying Oily Materials, of which the following is a specification.

It is well known that oily materials such as petroleum, heavy coal tar oils, and other 10 similar oily materials have been applied to roads, to the permanent ways of railways to mine galleries and other places or surfaces for purposes of disinfection, for preventing 15 the rising or scattering of dust into the air, and for other purposes.

Difficulties are encountered however in 20 the application of such oily materials to roads and other surfaces such as those mentioned above owing to its not being easy to apply or distribute the oily material in a 25 sufficiently fine state of sub-division and in sufficiently small quantities to achieve the purposes indicated above without incurring the disadvantages caused by distributing 30 the oily material unevenly or in too large quantities. Attempts have been made to overcome these difficulties by converting the oily material into a more or less permanent emulsion with water by the aid of some 35 emulsifying agent and applying the emulsion either with or without previous dilution with water to the road or other surface to be treated. In the preparation of these emulsions however, it is necessary to use a suffi- 40 cient proportion of an emulsifying agent to make the resulting emulsion so permanent that it may be transported and kept during a more or less indefinite time without the component oily material and aqueous solution separating to such an extent as would be deleterious to the ultimate purpose for 45 which the emulsion is to be used. The preparation of emulsions possessing the requisite degree of stability involves considerable cost.

The present invention is for the purpose of 50 applying oily materials in a very fine state of subdivision and in quantities which can be accurately regulated to any surface such as that of a road, or a railroad permanent way, of a mine gallery and the like without involving the necessity of previously preparing 55 storing and transporting an emulsion of the oily material with water or with an aqueous solution.

My invention consists in reducing the oily

material to a fine state of sub-division by the aid of any convenient appliance (such as a rotating drum or disk or a jet of steam or compressed air) attached to the portable apparatus which distributes the oily material upon the road or other surface and immediately the oily material has been reduced to such fine state of sub-division throwing it out upon the road or other surface by the aid of a spray, jet or stream of water. By this 60 method of procedure the oily material is retained in a fine state of sub-division during a length of time sufficient for it to reach the road or other surface to which it is to be applied before the particles of the oily material 65 coalesce or condense together and before the oily material thus separates more or less completely from the water or aqueous solution in which it is suspended in a fine state 70 of sub-division.

The way in which the invention may be carried out will be fully described with reference to the accompanying drawings:

Figure 1, longitudinal section of portable apparatus for sub-dividing the oil into fine 80 particles, mixing same with water and distributing upon roads or other surfaces. Fig. 2, transverse section of same. Fig. 3, longitudinal section showing a modified construction. Fig. 4, transverse section of same. 85

My invention is applied in a simple form by the aid of a watering or distributing cart or other portable apparatus constructed with reservoirs or tanks A and B, one or more tanks A to contain water and one or more 90 tanks B to contain oily material. The tank A is provided with a delivery valve a and the tank B with a delivery valve b by which the speed at which they discharge their contents can be accurately adjusted at any desired 95 rate. The apparatus is also provided with a centrifuge or rapidly rotating drum D into which the contents of the reservoirs A and B are discharged by the delivery valves a and b at regulated rates. The drum D is driven 100 from the axle of the portable apparatus by suitable gearing or otherwise (see Figs. 1 and 2.) The purpose and action of the centrifuge is to reduce the oily material to a fine state of sub-division and to mix it with the 105 water. The mixture of oily material and water expelled from the drum D of the centrifuge passes directly onto the surface to be treated through conveniently arranged distributing pipes E. 110

The drum centrifuge D in which the oily material is reduced to a fine state of sub-division may be replaced by a rapidly rotating disk D' upon which the oily material is allowed to fall from the delivery valve b (see Figs. 3 and 4). The horizontal circular metal disk D' upon which the oily material falls is rotated at a high rate of speed about a vertical axis by means of a driving arrangement actuated from the axle of the distributing cart or otherwise. The disk D' is enclosed in an annular chamber f by a casing F around the periphery of which the water from the tank A is admitted through the delivery valve a by a perforated pipe a'. As the oily material falls upon the rotating disk D' it is immediately thrown off in a fine state of sub-division, upon the sides F of the annular chamber down the sides of which water from the water reservoir A is caused to flow at a regulated rate. The finely divided particles of oily material are swept away by the stream of water into suitably arranged distributing pipes E from which the mixture of oil and water is discharged onto the road or other surface.

The appliance for finely dividing the oily material may be driven by a separate motor or in any other way which may be found convenient in place of being driven from the axle of the watering or distributing cart. Thus with a watering cart or the like driven by mechanical or electrical motive power it may be convenient to drive the centrifuge or like appliance by the aid of a separate motor driven directly from the main supply of mechanical or electrical power.

The water may be replaced by aqueous solutions such as sea water, chlorid of lime solution or other solution of disinfecting or deliquescent substances or the like and when found desirable one or more than one oily material may be reduced to a fine state of sub-division and distributed upon the road or other surface after admixture with one or more aqueous solutions in the same portable appliance.

The inventor has found that if the water or aqueous solutions used in the above described methods of applying his invention are mixed with the oily materials in the manners described above while at a temperature above the ordinary atmospheric temperature the admixture between the oily material and the aqueous solution and the reduction and maintenance of the oily material to and in a fine state of sub-division are promoted.

What I claim as my invention and desire to protect by Letters Patent is:—

1. The method of atomizing and emulsifying oily materials and applying same in a fine state of subdivision to road and other surfaces, comprising the dividing up of a small volume of the oil, drop by drop, by suitable revolving mechanism and carrying the same forward in the subdivided state by means of a large volume of an aqueous liquid substantially as described.

2. The method of atomizing and emulsifying oily materials and applying same in a fine state of subdivision to road and other surfaces which consists in supplying the oily material, drop by drop, rapidly atomizing the drops successively by mechanical means, carrying the atomized material forward by a large volume of aqueous liquid and applying the emulsion so formed directly to the road before the oily atoms can coalesce substantially as described.

3. The method of atomizing and emulsifying oily materials and applying same in a fine state of subdivision to road and other surfaces which consists in pouring a small volume of the oily material drop by drop into a rapidly revolving mechanism by which it is atomized, carrying the atomized material forward by a large volume of aqueous liquid and applying the emulsion so formed directly to the road before the oily atoms can coalesce substantially as described.

4. Apparatus for atomizing and emulsifying oily materials and treating roads and other surfaces therewith constructed with separate reservoirs for the oily material and for an aqueous liquid, delivery valves to deliver the oil and water in the desired proportions rapidly revolving mechanism by which the oil as it drops is atomized and pipes to distribute the admixture of water and oily material substantially as hereinbefore described.

5. Apparatus for atomizing and emulsifying oily materials and treating roads and other surfaces therewith constructed with separate reservoirs for the oily material and for an aqueous liquid, delivery valves to deliver the oil and water in the desired proportions; a rapidly revolving drum by which the oil as it drops is atomized, and pipes to distribute the admixture of water and oily material substantially as hereinbefore described.

In witness whereof, I have hereunto signed my name in the presence of two subscribing witnesses.

H. O. BRANDT.
